UNITED STATES PATENT OFFICE.

GUSTAF DE LAVAL, OF STOCKHOLM, SWEDEN,

CENTRIFUGAL CREAMER.

SPECIFICATION forming part of Letters Patent No. 335,344, dated February 2, 1886.

Application filed June 27, 1884. Serial No. 136,173. (No model.) Patented in England March 29, 1884, No. 5,682; in Belgium April 2, 1884, No. 64,717; in France April 2, 1884, No. 161,327; in Germany April 4, 1884, No. 29,218, and in Luxemburg April 4, 1884, No. 378.

To all whom it may concern:

Be it known that I, GUSTAF DE LAVAL, of Stockholm, in the Kingdom of Sweden, have invented an Improvement in Centrifugal Creamers or Separators, (for which invention Letters Patent have been granted to me in Great Britain, dated March 29, 1884, No. 5,682; in Belgium, dated April 2, 1884, No. 64,717; in France, dated April 2, 1884, No. 161,327; in Germany, dated April 4, 1884, No. 29,218; in Luxemburg, dated April 4, 1884, No. 378, and for which I have made application for patent in Russia on the 6th day of April, 1884, but no patent has yet been granted 15 on such application,) of which the following is a specification.

Centrifugal separators have been made in which there is an annular delivery-lip, as in my Patent No. 247,804, and the two fluids 20 discharged from the separator have been received into vessels with spouts, as seen in my said patent and in the French Patent No. 105,716, November 19, 1874.

In my present improvements the fluids are 25 separated and delivered from annular lips and received into recessed rings having discharge-pipes, the proportionate quantity discharged being regulated by the proximity of the discharge-lips to the surface of the ring, 30 and the centrifugal force being availed of to project the liquids through the discharge-pipes.

This improvement is available with the 35 vertical centrifugal separator shown in my Patents Nos. 293,314 and 249,731, but it is especially available with a horizontal separator. In said separator the discharged liquids are driven off by pipes in consequence of the centrifugal force acting upon the liquids 40 to revolve it within the annular recess and project it through the discharge-pipes that lead the liquid to any desired points of delivery.

I supply the liquids to be separated at the 45 center of the horizontal centrifugal vessel, and such liquid passes gradually toward the other end, and the liquids separate according to gravity, and are discharged at the other end from two or more outlets.

In the drawings, Figure 1 is a longitudinal 50 vertical section of the separating apparatus. Fig. 2 is a cross-section at the line *x x*. Fig. 3 is a longitudinal section, and Figs. 4 and 5 cross-sections at *y y* and *z z*, respectively, of a modification in said apparatus. Fig 6 is a 55 vertical section of the improvement as applied to a vertical separator, and Fig. 7 is a horizontal section at the line *u u*.

The vessel *A* may be cylindrical, as in Figs. 1 and 3, or elliptical, as in Fig. 6, and the 60 shaft *m* for the same may extend through the vessel *A*, as in Fig. 1, or it may be at the ends of the vessel only and tubular, as in Fig. 3, or it may be below the vessel *A*, as in Fig. 6. The bearings *p q* for the shaft *m* may be of any 65 desired character, and they do not form any part of this present invention, and the frame or supports *L* are constructed with reference to properly holding the bearings and the case *Q* surrounding the centrifugal chamber. 70

The milk or other liquid to be separated is to be supplied into the centrifugal separator *A* in any suitable manner. In Fig. 1 the vessel *d* is shown with a pipe, *o*, to allow the milk to run into the shell *e*, from which the pipes 75 *e'* discharge the same into the vessel *A*. In Fig. 3 the pipe *o* is applied at the end of the hollow axis *m*, and from the latter the pipe *e'* discharges the milk into the vessel *A*. In Fig. 6 the pipe *o* leads into the vessel *A*, and the 80 shell *e* and tubes *e'* are within said vessel *A*.

The annular discharge-lips *a* and *a'* are upon or connected with the vessel *A* and revolve with the same. The lip *a* is preferably of less diameter than the lip *a'*, and the cream and 85 skim-milk are delivered to the respective annular lips, the latter by the pipe *C* from the interior of vessel *A*, the cream passing over the mouth of the vessel *A* or through the tubular journal, Fig. 3. Around these annular 90 discharge-lips *a a'* there are the stationary receiving-rings *h h'*, having the annular recesses, from which pass off the pipes *c c'*. These pipes 95 *c c'* are preferably tangential to the bottoms of the annular recesses, and the faces or flat portions of the lips are at the proper distance from the interior surfaces of the respective receiving rings or recesses *h h'*, to allow the

necessary space for the discharge of the liquids or fluids. The cream, being lightest in its specific gravity, accumulates nearest the axis of rotation of the separator and passes off 5 from the annular lips a , and the skim-milk, being heaviest, passes by the pipe C to the annular delivery-lip a' .

The grooved or inner surfaces of the annular recesses are parallel, or nearly so, with the 10 exterior surfaces of the annular discharge-lips, and in consequence of the speed with which the liquid is thrown off by the edges of the lips a or a' such liquid continues to rotate in the annular recess or ring h or h' until it passes off 15 by the pipes c or c' , and the force is sufficient to elevate the liquid, if required, by the pipes v v' . (Shown by dotted lines in Fig. 2.)

The centrifugal vessel is adjustable in the 20 tine of its axis, so as to vary the distance between the respective surfaces of a a' and h h' . For this purpose the screw g and spring f may be used, as in Fig. 1, or the screw g , Figs. 3 and 6, thereby regulating the discharge of the 25 respective fluids according to the width of the escape-openings. In either instance the axis of the centrifugal separator being moved endwise by the action of the screw g , the lips a a' are moved toward or from the surfaces of the recessed rings h h' . If these rings are made 30 adjustable axially of the separator, the same effect will be produced.

In the apparatus shown in Figs. 1 to 5 it is preferable to cleanse the same after use by hot water passed in in place of the milk. The 35 supply of milk may be from any convenient source. In Fig. 1 it is from the vessel d , and in Figs. 3 and 6 it is by the pipe o . According to the quantity supplied so will be the combined discharge, and this will be proportioned at the two or more places of delivery 40 according to the relative sizes of openings. It is to be understood that either or both rings h h' may be adjustable. In consequence of the cylinder A being long in comparison to its diameter, the fluids will remain in the same a 45 longer time than in the apparatus heretofore patented by me.

It will be apparent that there must be at least two discharge-openings; but it is not necessary that both shall be provided with the 50 same annular discharge-lips and ring.

I am aware that the liquids have been discharged from annular lips and received into recesses or vessels, as in aforesaid French patent and others; but the liquid runs from the 55 vessels by gravity. In my improvement the centrifugal action of the separator is continued after the liquids are delivered from the lips.

I claim as my invention—

1. The combination, with a centrifugal separator, of two parallel discharge-lips, each of which is a flat ring, from the outer edge of which the liquid is delivered, two stationary receiving-rings surrounding and in close proximity to such lips and pipes connected with the same, and mechanism, substantially as specified, for adjusting the parts axially of the separator to vary the discharge-opening between the annular discharge-lips and the receiving-rings, substantially as set forth. 70

2. The combination, in a centrifugal separator, of a rotative vessel, tubular axis for the same, bearings for supporting the axis, and means for rotating the vessel, a supply-pipe to one of the tubular axes, two parallel circular 75 lips, each of which is a flat ring, from the edge of which the liquid is delivered, two recessed ring-receivers, one at each of the discharge-lips, and a pipe extending from one of the discharge-lips to near the interior of the centrifugal separator, and means, substantially as specified, for adjusting the parts to vary the discharge-openings, substantially as set forth. 80

3. A centrifugal separator having a discharge-lip in the form of a flat ring, in combination with a stationary receiving-ring the inner surface of which is a similarly-shaped groove, and a pipe passing off from such groove, the inner surface of the receiving-ring being sufficiently near to the annular discharge-lip 90 for the liquid in such groove to receive a revolving motion and be projected by the centrifugal action through the pipe, substantially as specified. 85

Signed by me this 12th day of March, A. D. 95 1884.

GUSTAF DE LAVAIS.
